UNITED STATES PATENT OFFICE.

JOHN M. FITZGERALD, OF OAK PARK, ILLINOIS, ASSIGNOR TO ASBESTOS PROTECTED METAL COMPANY, OF PITTSBURGH, PENNSYLVANIA, A CORPORATION OF PENNSYLVANIA.

CONDUIT.

1,306,142.

Specification of Letters Patent. Patented June 10, 1919.

Application filed June 15, 1917. Serial No. 174,860.

To all whom it may concern:

Be it known that I, JOHN M. FITZGERALD, a citizen of the United States, and a resident of Oak Park, in the county of Cook and State of Illinois, have invented an Improvement in Conduits, of which the following description, in connection with the accompanying drawings, is a specification, like characters on the drawings representing like parts.

This invention relates to a conduit of the character known as trunking and capping which is employed among other uses for signaling work on steam railway systems.

Conduits of the character described are now commonly made of wood and comprise a trough-shaped lower or trunk member in which the insulated wires or conductors are laid, and a cap or cover member composed of a single strip or piece of wood extended longitudinally of the trunk member or of a plurality of short strips or pieces extended transversely of the trunk member and secured thereto by nails or other fastening devices.

Conduits of this construction are laid lengthwise of the steam railway tracks and have laterals or branches which extend transversely of the track under the rails thereof, which latter are in most cases employed as part of the signaling system.

These wooden conduits afford limited mechanical and electrical protection for the wires or conductors laid in them, but they are open to serious objections, one of which is the inaccessibility of the contents of the conduit, for when it is desired to lay new wires or conductors or replace old or defective wires, a material length of time and labor is required to remove the cover, which is often damaged in so doing.

Another objection is the short life of the wooden conduit due to the action of the weather, assisted frequently by the wear and tear upon the cover by persons walking upon the same.

Still another objection is the liability of destruction by fire, caused in many cases by sparks and hot cinders from passing trains, and destruction by fire is generally attended by short circuiting or other derangement of the signaling system by the melting of the

insulation on the wires, and derangement of the signaling system is not only expensive but highly dangerous on account of the liability of accidents from running trains without a signaling system.

The present invention has for its object to provide a conduit of the trunking and capping character, which affords access to its contents substantially in an instant, with the least possible labor and expense and without impairing the usefulness of the conduit.

The invention further has for its object to provide a conduit of the desired accessibility, which affords permanent mechanical protection for the contents within the conduit, which is fire and weather-resisting, and electrically insulating, which is of minimum weight yet strong, which can be placed in operative position manually and without requiring machinery for this purpose, which can be assembled in a minimum time and with a minimum of labor without the use of nails or other fastening devices.

To this end the conduit is provided with a substantially trough-shaped trunk member having side walls, and with a substantially trough-shaped cap member having side walls, said cap member co-operating with the trunk member to close the latter at its top and have the side walls of one member extended into the other member between the side walls of the latter member.

The substantially trough-shaped trunk and cap members may be made of sheet metal or other suitable material and provided with one or more layers of protective material, and it may be preferred to make said members of sheet metal provided with layers of asbestos paper adhesively attached to the metal by bituminous cement and covered on their exterior by a protective coating.

It is preferred to make the cap and trunk members of such relative size as to obtain frictional engagement of the side walls of said members and thereby obtain an effective weather-tight joint between the protective coatings on said side walls, and it is also preferred to provide said side walls with means for automatically locking them together, as will be described.

These and other features of this invention will be pointed out in the claims at the end of this specification.

Figure 1 represents a sufficient portion of 5 a railway system provided with a conduit system embodying this invention, to enable the latter to be understood.

Fig. 2, a side elevation of a portion of 10 the conduit shown in Fig. 1.

Fig. 3, a detail in section of the conduit having opposing branches.

Fig. 4, a cross section on an enlarged scale 15 of the conduit shown in Fig. 1.

Fig. 5, an enlarged cross-section on the line 5-5, Fig. 2, and Fig. 6, a detail of the 20 protected metal preferred by me.

Referring to the drawing, *a*, *b*, represents 25 the tracks of a steam railway system provided with a signaling system, represented by the wires or electric conductors *c*, which are contained in a conduit of the trunking and capping character and which is herein shown as composed of a main line conduit *d* provided with laterals or branches *e*, which extend under the rails of the 30 tracks *a*, *b*.

The main line and the branch conduits are of like construction, and consist of a 35 substantially trough-shaped trunk or lower member 10 and a substantially trough-shaped cap member 12. The trunk member 10 is provided with a bottom wall 13 and substantially upright side walls 14, and the cap member 12 is provided with a top wall 15 and substantially upright side walls 16. The cap member 12 is preferably made 40 of sufficient width to fit over upon the upright side walls 14 and have its top wall 15 rest thereon, and also have its side walls 16 frictionally engaged with the side walls 14.

The main line conduit *d* is composed of a 45 plurality of sections of cap and trunk members 12, 10, which are arranged so that the sections of the cap member break joints with the sections of the trunk member as clearly represented in Fig. 2.

In practice, the trunk sections are 50 designed to rest upon and be secured to suitable supports, which are spaced apart at intervals, preferably about five feet. The support referred to may be of any suitable construction or material, but it is preferred to make them as represented in Fig. 5, wherein 55 represents a metal chair or plate, provided with a center rod or pipe 21, which is extended into a concrete base or support 22. The chair 20 may and preferably will be provided with side uprights or flanges 23. The sections of the trunk member 10 are laid 60 in the chairs 20 and may be fastened thereto by suitable devices, such as wire nails or rods 24, which are passed down through holes in the bottom of the trunk member and through the chair and have their projecting ends fastened against displacement.

as by turning them under the chair. The sections of the trunk member are butted together, with their meeting ends resting on a chair.

The sections of the cap member are then 70 placed over the trunk member as represented in Fig. 4, with the ends of the individual cap sections on opposite sides of the chair on which the abutting ends of two adjacent trunk sections rest, so that the joint formed 75 by said ends is covered by a solid part of the cap member, as clearly shown in Fig. 2.

The ends of adjacent cap sections may 80 abut if desired, but it may be preferred to leave a slight space between them as represented in Fig. 2, and to cover said space by a saddle or strap 25, which is secured to the chair 20 by bolts 26 or otherwise.

The saddles or straps 25 serve as removable clamps to firmly secure the conduit to 85 its support and hold it in place. The space between the cap sections affords opportunity for the insertion of a hook or other device under the end of a cap section, when it is desired to remove the latter from the trunk 90 member to gain access to the interior of the conduit.

When the cap section is to be removed as 95 described, the saddle or strap 25 is first removed so as to uncover the space between adjacent cap sections.

In this way, access to the interior of the 100 conduit may be had in a minimum time and with minimum labor and without injuring or impairing the usefulness of the cap member.

The cap member may be automatically locked to the trunk member by providing beads 27 in the side walls of the cap member which engage corresponding beads 28 in the 105 side walls of the trunk member.

The beads 27 in the cap member are capable of being manually withdrawn from the beads in the trunk member.

The trunk member is designed to have the 110 electric conductors or wires *c* laid in it, as practised with the wooden conduits now commonly employed on steam railway systems.

The substantially trough-shaped cap and 115 trunk members may be made of any suitable material, but it is preferred to make them of sheet metal and to provide the latter with protective coatings, and as represented in Figs. 4 and 6, the sheet metal element of the 120 trunk member comprises the bottom 13 and side walls 14, and is represented as provided on its inner and outer surfaces with a coating of a bituminous composition, represented by the heavy black lines 30, which serves to 125 protect the sheet metal element and also serves as an adhesive for layers 32, of fibrous material, preferably asbestos paper, wool felt, mineral wool and the like, which are also protected by coatings 34 of suitable 130

weather-resisting material. The sheet metal element of the cap member comprises the top 15 and side walls 16, and is protected by the coating 30, fibrous layers 32, and coating 34.

5 The branches or laterals *e* from the main line conduit *d* may be made of one or more sections, according to the length of the lateral, and extend under one and often under both rails of the track.

10 It is preferred to make the cap and trunk members of protected metal, as by so doing the signal wires *c* are given maximum protection, inasmuch as the metal elements of the cap and trunk members afford permanent mechanical protection, and the layers 30, 15 32, 34, afford protection against the weather, fire, gases and fumes, and also serve to insulate the contents of the conduit.

15 It is not desired to limit the invention to the use of the conduit for electric signaling systems, as it may be used to advantage for other purposes, both for exterior and interior work.

Claims.

20 1. A conduit of the character described, comprising a sheet metal trunk member having a bottom wall and side walls and provided with a fire and weather resisting protective coating on their exterior and interior 25 surfaces, and a sheet metal cap member having a top wall and side walls and provided with a fire and weather resisting protective coating on their exterior and interior surfaces, said cap having the protective coating 30 on one surface of its side walls frictionally engaged with the protective coating on one surface of the side walls of said trunk member to make a weather-tight joint between said side walls.

35 2. A conduit of the character described, comprising a substantially trough-shaped trunk member having a bottom wall and

side walls extended therefrom and composed of sheet metal and fire and weather-resisting layers adhesively affixed to the inner and outer surfaces of said sheet metal, and a substantially trough-shaped cap member having a top wall and side walls extended therefrom and composed of sheet metal and layers of fire and weather-resisting layers 45 adhesively affixed to the inner and outer surfaces of the sheet metal of said cap member, said cap member coöperating with said trunk member to close the latter at its top and have the fire and weather-resisting layers 50 of the side walls of said members in contact to form weather-tight joints between said side walls.

3. A conduit of the character described, comprising a substantially trough-shaped 60 trunk member composed of a sheet metal element, layers of fire-resisting fibrous material adhesively affixed to the inner and outer surfaces of said metal element and a weather-resisting protective coating on the 65 exterior of said fibrous layers, and a substantially trough-shaped cap member coöperating with the said trunk member to close the latter at its top and composed of a sheet metal element, layers of fire-resisting fibrous 70 material adhesively affixed to the inner and outer surfaces of the last-mentioned metal element, and a weather-resisting protective coating on the exterior of said fibrous layers, the protective coating on the inner surfaces 75 of the side walls of one member engaging the protective coating on the outer surfaces of the side walls of the other member to form a weather-tight joint between said side walls.

In testimony whereof, I have signed my name to this specification.

JOHN M. FITZGERALD.
